UNITED STATES PATENT OFFICE.

WILLIAM M. BAUER, OF CHICAGO, ILLINOIS.

PIANO-PEDAL.

SPECIFICATION forming part of Letters Patent No. 655,388, dated August 7, 1900.

Application filed April 21, 1900. Serial No. 13,682. (No model.)

To all whom it may concern:

Be it known that I, WILLIAM M. BAUER, a citizen of the United States, residing at Chicago, in the county of Cook and State of Illinois, have invented a new and useful Improvement 5 in Piano-Pedals, of which the following is a specification.

My invention relates to an improvement in the pedal mechanism of a piano, either up- 10 right or grand.

My object is more especially to provide flexible fulcrum or connecting means of improved construction for the pedals, which will obviate all danger of squeaking, prevent torsional 15 movement of the pedals, and operate as particularly durable and effective means for their purpose.

In the drawings, Figure 1 is a plan view of the pedals and pedal-levers of an upright 20 piano provided with my improvements; Figs. 2, 3, and 4, enlarged sections taken, respectively, on lines 2, 3, and 4 of Fig. 1 in the directions indicated by the arrows; Fig. 5, an enlarged broken perspective view of the flexible 25 fulcrum of a pedal; Fig. 6, an enlarged section taken on line 6 of Fig. 1 and showing one of the springs which serve to return the pedals; Fig. 7, a section taken on line 7 of Fig. 6, and Fig. 8 a detail of construction.

30 A is the bottom board, and A' the pedal-rail, of a piano-casing.

B, C, and D are pedals serving the usual purpose, and a b c pedal-levers. The levers a b c are formed with mortises d to fit over 35 tenons e' at the tops of blocks or lever-supports e.

E are pedal-springs fastened by means of screws to the tenons e' and levers, as indicated in Fig. 6. The springs E are noiseless 40 in action and serve to hold the levers in the horizontal plane out of contact with the tenons e'.

The middle pedal C is straight and is fulcrumed between its ends, as shown in Fig. 3. 45 The pedals B and D are curved to extend laterally to the left and right and are fulcrumed at their rear ends, as shown in Fig. 2.

F is a stationary block or pedal-support provided on its upper side, between ends, with a 50 recess f and provided near the opposite ends with openings g.

G is a horizontal plate of comparatively

thin flexible metal, provided midway between its ends with an opening h. Fitted upon each end portion of the plate G is a strengthening-plate G', of stiff metal. Extending through the opening h of each plate G is a plate or strip H, of comparatively thin flexible metal, and fitted against the opposite end portions thereof are stiff metal strengthening-plates 55 H'. Plates G and H are provided at each of the pedals to form the fulcrums thereof. At the pedals B D the plates G are fastened along their rear end portions against the upper sides of the openings g and along their 60 forward end portions along the upper sides of the rear end portions of the pedals. The plates H are fastened along their upper end portions against the forward face of the block F and along their lower end portions against 65 the rear ends of the pedals, all as indicated most clearly in Figs. 2 and 5. The parts may be fastened together with screws, as shown, the plates G' H' operating as jam-plates to strengthen and stiffen the fastenings and 70 render them flexible only between the jam-plates. The plates or strips H extend through the openings h in a manner to be out of contact with the plates G. The fulcrum-plates 75 form pivotal connections between the pedals and stationary block F, permitting the pedals to swing easily and without friction in the vertical plane. The plates operate together to hold the pedals when subjected to torsional strain against twisting at their fulcrums. It 80 will be understood that pressure of the foot upon the laterally-projecting ends of the pedals B and D subjects them to torsional strain, and all bent pedals hitherto provided for pianos of which I am aware yield more 85 or less under such strain, which is objectionable. Any twisting of the pedal at the fulcrum when operated tends to distort the parts and produce a squeaking noise. My improvement not only adds greatly to the 90 durability of the connection, but also overcomes all danger of torsional yielding and of squeaking. The pedal C, though not subject to the same torsional strain, is preferably provided with plates G H and strengthening- 95 plates G' H', as described. All the plates G' and H' are preferably curved longitudinally, as indicated in Fig. 8, so that when screwed in place they flatten against the plates G H, fit- 100

ting with especial closeness at the ends to prevent any danger of vibration between the parts which would produce noise. The plate G at the middle pedal is attached along one end 5 portion to the upper surface of the pedal, as shown in Fig. 3, and along its forward end portion against the under side of the pedal-rail A', which forms the pedal-support. The strip or plate H is fastened along its lower 10 end against a vertical shoulder *i* of the pedal and along its upper end against the rear of the pedal-rail A'. The strengthening-plates G' H' serve the same purpose as before described.

15 The pedals B and D are connected between their ends, in a common manner, by means of the rods *k* with the levers *a c*, and the connection between the rear end of the pedal C and the lever *b* is by means of the confined 20 post *l*. The springs E on the levers *a c* operate to hold the said levers normally in the horizontal plane and sustain the forward ends of the pedals in their normally-raised positions. The spring E on the lever *b* tends to 25 resist rise of the rear end of the pedal C and consequent lowering of the forward end of said pedal. Thus the pedal-springs E serve to contribute the desired resistance to lowering of the pedals and to return the pedals, 30 while the plates G H operate merely as flexible fulcrums. Between the surfaces of metal and wood and wherever one moving part strikes or may strike another suitable felt muffles are provided, as indicated in the 35 drawings.

While I have described my improvements minutely with regard to form and details of construction, I do not desire to be unduly limited thereto, because my improvements 40 may be variously modified in the matter of

form and details of construction without departing from the spirit of the invention as defined by the claims.

What I claim as new, and desire to secure by Letters Patent, is—

45 1. In a piano, the combination of a pedal-lever supporting-block, a pedal-lever, a pedal-raising spring connecting the pedal-lever and said supporting-block, a pedal-support, a pedal, a connection between the 50 pedal and said lever, and a torsional strain-resisting flexible-metal-plate connection separate from the pedal-raising spring between the pedal and pedal-support, whereby said plate connection operates as a torsional strain-resisting fulcrum for the pedal, and the pedal 55 is raised by the pedal-raising spring.

2. The combination with the pedal and pedal-support, of a plate of flexible metal having an opening through it fastened at opposite sides of its opening to said support and pedal respectively, and a strip of flexible metal extending at an angle to said plate through the opening therein and fastened on opposite sides of said plate to the said support and pedal respectively, said plate and strip operating as the fulcrum of the pedal. 60

3. In a piano, the combination of a pedal-lever support *e* having a tenon *e'*, a pedal-lever having a mortise *d* into which the tenon 70 extends, a spring E fastened to the lever and tenon and forming the sole connection between the said lever and support, a pedal-support, a pedal connected with the pedal-lever, and a flexible-metal-plate connection 75 between the pedal and pedal-support.

WILLIAM M. BAUER.
